UNITED STATES PATENT OFFICE

AUGUST MITCHELL, OF NEW YORK, N. Y., ASSIGNOR TO THE CHASE COMPANIES, INCORPORATED, OF WATERBURY, CONNECTICUT, A CORPORATION OF CONNECTICUT

DESIGN FOR A FLASH LIGHT

Application filed August 22, 1931. Serial No. 40,906. Term of patent 14 years.

To all whom it may concern:

Be it known that I, AUGUST MITCHELL, a citizen of the United States, residing at New York, county and State of New York, have invented a new, original, and ornamental Design for Flashlights, of which the following is a specification, reference being had to the accompanying drawings, forming a part shown hereof:

Fig. 1 is a plan view of a flashlight showing my new design;

Fig. 2 is a side elevation of the flashlight showing my new design, and

Fig. 3 is a perspective view of the flashlight showing it supported at an angle as when in use.

I claim:

The ornamental design for a flashlight, as

AUGUST MITCHELL.
